(57) **CLAIM**

The ornamental design for a mobile radio housing, as shown and described.

DESCRIPTION

FIG. 1 is a front, top, and right side perspective view of a mobile radio housing showing our new design;

FIG. 2 is a right, side-elevational view thereof, the left side being a mirror image;

FIG. 3 is a rear elevational view thereof;

FIG. 4 is a top plan view thereof;

FIG. 5 is a bottom plan view thereof; and,

FIG. 6 is a front, bottom, and left side perspective view thereof.

The broken lines showing the mobile radio control head portion of FIGS. 1, 2, 4, 5, and 6 are for illustrative purposes only and form no part of the claimed design.
